(57) **CLAIM**

The ornamental design for a transceiver, as shown and described.

DESCRIPTION

FIG. 1 is a front, left-side, perspective view of a transceiver showing my new design, an antenna is shown in a down position;

FIG. 2 is a rear, right-side, perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a front view thereof, the antenna is shown in an up position.

The broken line showing in the drawings is for illustrative purposes only and forms no part of the claimed design.
